APPARATUS FOR PRODUCING A HEATED
GASEOUS MEDIUM

Rallston M. Sherman, Glastonbury, Conn., assignor to The Silent Glow Oil Burner Corporation, Hartford, Conn., a corporation of Connecticut

Application December 15, 1949, Serial No. 133,103

4 Claims. (Cl. 263—19)

1

My invention relates to the production of heated gaseous mediums, the heat of which is derived by burning fluid fuel, so as to enable the heat generated by combustion of such fuel to be conveyed to a more or less distant place.

The invention, which has among its objects the production of a heated gaseous medium while effecting proper combustion of the fuel, will be best understood from the following description when read in the light of the accompanying drawing of an embodiment of the invention, while the scope of the invention will be more particularly pointed out in the appended claims.

The drawing is an elevation, with parts broken away and parts in section, of a form of the invention in which the fluid fuel employed is in the form of fuel oil.

In the form of the invention illustrated by the drawing there is provided an inner or combustion chamber 1 having the cylindrical lateral wall 3 and end walls 5 and 7. The cylindrical wall is shown as provided with small relatively closely spaced perforations 9. These perforations are distributed over the entire cylindrical surface, while, as shown, the end walls are imperforate except for the central opening 11 formed in the end wall 5. However, if desired, the perforations 9 also may extend over the end wall 7.

The opening 11 of the end wall 5 receives the discharge end section 13 of an air conduit 15 comprising an intermediate section 17 carrying at one end the section 13 and communicating at its opposite end with a section 19 forming part of a conventional gun-type oil burner. This burner comprises a casing portion 21 containing an electric motor driven fan or blower 23 for forcing atmospheric air through the air conduit 15 into the combustion chamber 1, the amount of air discharged by the fan being regulated in the usual manner by adjustable shutters (not shown) positioned at one end of such casing portion, which shutters control the size of the air intake to the fan. As in the conventional gun-type oil burner, the pump 25, driven by the same motor as the fan, draws fuel oil from the tank 27 and discharges it under pressure into a pipe 29 in communication with an oil conduit or pipe 33 positioned axially of the air conduit 15, the pipe 33 having at its end adjacent the combustion chamber 1 a spray nozzle 35 for atomizing or comminuting the fuel oil. The fuel oil so atomized enters the combustion chamber 1 admixed with the air discharging from the ad-

2

jacent end of the air conduit 15. The nozzle is so designed as to secure the desired pattern of flame produced by the mixture when it is burned in the combustion chamber 1 and the desired amount of oil supplied the combustion chamber. Preferably positioned in the section 13 of the air conduit 15 is a circumferential series of vanes 37 for causing a whirling action of the air discharged into the combustion chamber 1 from the conduit so as thoroughly to mix the air with the atomized oil. The burner, as shown, is provided with an ignition spark device 39 for igniting the mixture, and preferably is provided with the usual controls for governing the operation of the burner in accordance with the temperature conditions of the space to be heated by the gaseous medium produced by the apparatus.

Surrounding the drum or combustion chamber 1 with its walls in spaced relation thereto is shown an outer drum or chamber 41 having the lateral cylindrical wall 43 and opposite end walls 45 and 47, the end wall 45 being provided with an opening 49 to permit passage therethrough of the section 17 of the air conduit 15, while the end wall 47 has a central opening with which communicates a conduit 51 for conducting the heating medium produced by the apparatus to the space to be heated as, for example, to the heating flues of a tobacco or other crop storage or crop curing barn.

As shown, the section 17 of the air conduit 15 is provided with perforations 53 forming an opening which permits the bulk of the air forced through the air conduit 15 by the fan 23 to enter the space between the inner and outer drums or chambers 1 and 41 for passage therethrough and discharge into the conduit 51. This air is heated by contact with and radiation from the hot walls of the inner or combustion chamber 1, and mixes with the gaseous products of combustion discharged into such space from the combustion chamber through the perforations 9 for further augmenting the heat of the gaseous medium thus produced.

In respect to the amount of oil burned in the combustion chamber 1, the fan 23 is of oversize because of the bulk of the air forced by it discharging through the perforations 53. Preferably the amount of air discharged through these perforations will be such as to maintain the hottest portions of the walls of the outer chamber 41 and conduit 51 at as high a temperature as possible, say 650° F., but without causing them at any point to glow so as to avoid creation of a fire hazard. Ordinarily this will

necessitate discharge through the perforations of from about 70 to 80% of the air supplied by the fan, the remainder of the air discharging into the combustion chamber 1 in the form of air admixed with the atomized oil, with the result that a very large volume of heated gaseous medium is produced by the apparatus for discharge through the conduit 51.

The combination chamber 1 preferably is identical with that described in applicant's pending application Serial Number 115,090, filed September 10, 1949, and preferably the burner is operated in identically the same way. As described in said application, complete combustion of the oil may be secured by having in the combustion chamber a flame of such pattern that it does not contact with the walls of said chamber, the oil being burned at such rate that the perforated area of the chamber throughout its extent is heated to incandescence, say from 900 to 1500° F. Such complete combustion will result in the gaseous medium produced by the present apparatus containing no inflammable products, and will render it odorless and smokeless, for with complete combustion the gaseous combustion products escaping through the perforations 9 will consist wholly of carbon dioxide, oxygen and nitrogen.

Preferably the space between the two chambers 1 and 4 is such, with relation to the amount of air supplied that space and the amounts of air and oil supplied the chamber 1 and the heat generated, that the pressure in the chamber 1 is very slightly in excess of that in the space between the two chambers so as to prevent entrance of air from such space into the chamber 1 through the perforations 9. Were such air permitted to enter the chamber 1 through the perforations, or were the flame within that chamber permitted to contact with its perforated wall portions so that unburned products of the vaporized oil would escape through said perforations, complete combustion of the oil would not occur. Under any ordinary conditions the difference in pressures mentioned need amount only from about 0.0008 to 0.006 inch of water. The pressure in the space between the two chambers, however, can be such as is requisite to force the heated medium to the place where it is to be used, or an exhaust fan or blower associated with the conduit 54 may be employed for that purpose, such fan or blower when employed, of course, acting to draw the heated medium from the space between the two chambers so as to tend to reduce the pressure in that space and in that way act as well as the fan or blower 23 to determine the amount of air passed through such space and therefore the actual pressure maintained in it.

As further pointed out in the above mentioned application, to secure complete combustion the perforations 9 should not exceed approximately 0.15 inch in diameter or otherwise have a cross-sectional area greater than that approximately represented by a circular perforation of such diameter, the perforations preferably being as small as can be economically produced. Furthermore, to secure complete combustion within the combustion chamber, the total area presented by the perforations per square inch of perforated surface should be from approximately 0.05 to 0.14 square inch, while the sheet metal constituting the perforated portion of the combustion chamber should be as thin as structural requirements will permit, refractory sheet metal, such as stainless steel, about $\frac{1}{2}$ inch thick giving satis-

factory results in most situations. Furthermore, as pointed out in said application, to secure combustion the cubical contents of the combustion chamber should be from approximately 2300 to 4000 cubic inches per gallon of oil burned therein per hour, with the total perforated surface of the chamber expressed in square inches from 15 to 35% of the arithmetical value of the cubical contents of the chamber expressed in cubic inches.

Various kinds of oils may be burned, satisfactory results having been secured with ordinary commercial gasoline, kerosene, and all grades of fuel oil up to so-called No. 3 fuel oil.

When a cylindrical combustion chamber is employed the relation between its diameter and its length is not critical, satisfactory results having been secured where the length of the chamber is from 100 to 400% of its diameter. Examples of these cylindrical combustion chambers are those 15 inches in diameter and 18 inches long, 22 inches in diameter and 24 inches long, 22 inches in diameter and 36 inches long, and 26 inches in diameter and 30 inches long. Other proportions between the length and diameter of the combustion chamber however may be employed, and satisfactory results have been secured with combustion chambers the lengths of which are less than their diameters, for example, a combustion chamber 22 inches in diameter and 18 inches long.

The amount of air admixed with the atomized oil may be that commonly employed in connection with domestic oil burners, preferably an amount of air which will give a bright orange flame. However, lesser amounts of air may be employed down to that which will give a blue flame. It is advisable, as in the ordinary case of combustion apparatus, to keep the excess amount of air admixed with the atomized oil at a minimum consistent with securing satisfactory operation, as otherwise the temperature of the combustion products will be unduly decreased. In accordance with common practice this amount of air should be such as to give a rather small amount of excess oxygen in respect to the amount thereof which will stoichiometrically secure complete combustion, namely, from about 8 to 15% excess oxygen, preferably from about 10 to 12%.

It will be understood that within the scope of the appended claims wide deviations may be made from the form of the invention described without departing from the spirit of the invention.

I claim:

1. Apparatus for producing a heated gaseous medium comprising walls forming a combustion chamber having an opening, at least a portion of which walls is formed with a multitude of spaced small perforations other than said opening, which perforations constitute substantially the sole means of escape of combustion products from said chamber, means for heating said walls comprising burner means for entering into said chamber through said opening a blast consisting of fluid fuel mixed with requisite air for supporting substantially complete combustion of such fuel in said chamber, which burner means constitutes substantially the sole means for supplying air to said chamber, that air being contained in said mixture so supplied said chamber, walls at the exterior of said combustion chamber forming with said combustion chamber a second chamber with which said perforations directly communicate for discharging combustion products from said combustion chamber into said

second chamber; the said walls at the exterior of said combustion chamber being provided with air admission and discharge openings for said second chamber, blower means for passing air through said second chamber from said admission opening to said discharge opening for contact with said perforated wall portion of said combustion chamber and in such amounts as to maintain a pressure in said second chamber less than that maintained in said combustion chamber by the blast of mixture entered into it and combustion of said mixture therein, whereby to heat the air so passed and mix it with said combustion products to form the heated gaseous medium while preventing flow of air from said second chamber to said combustion chamber through said perforations.

2. Apparatus for producing a heated gaseous medium comprising walls forming a combustion chamber having lateral and end walls, which lateral walls are formed with a multitude of spaced small perforations constituting substantially the sole means of discharge of combustion products from such chamber, walls in opposed spaced relation to the first mentioned walls forming an outer chamber having a discharge opening, into which outer chamber said perforations directly open for discharging into said outer chamber products of combustion from said combustion chamber, burner means for entering into said combustion chamber through one of its end walls a blast directed toward its opposite end wall consisting of fuel oil mixed with requisite air for supporting substantially complete combustion of such fuel in said chamber, which burner means comprises a fuel oil conduit and an air conduit and means for supplying said conduits with oil and air respectively, under pressure for forming said blast, the fuel oil conduit having at its discharge end an oil atomizing nozzle adapted to discharge into said combustion chamber a spray of oil of such shape as to produce a flame of such pattern in said combustion chamber that it is in out of contacting relation to the walls of said combustion chamber, said air conduit also having an outlet for discharging air into said outer chamber for flow therethrough to the discharge opening of said outer chamber in contact with the walls of said combustion chamber and in such amounts as to maintain a pressure in said outer chamber which is less than the pressure maintained in said combustion chamber by said blast of mixture entered into said combustion chamber and combustion of said mixture therein whereby to prevent flow of air through said perforations into said combustion chamber.

3. Apparatus for producing a heated gaseous medium comprising walls forming a combustion chamber having lateral and end walls, which lateral walls are formed with a multitude of spaced small perforations constituting substantially the sole means of discharge of combustion products

from such chamber, walls in opposed spaced relation to the first mentioned walls forming an outer chamber having a discharge opening, into which outer chamber said perforations directly open for discharging into said outer chamber products of combustion from said combustion chamber, burner means for entering into said combustion chamber a blast consisting of fuel oil mixed with requisite air for supporting substantially complete combustion of such fuel in said chamber, which burner means constitutes substantially the sole means for supplying air to said combustion chamber, that air being contained in said mixture, and comprises a fuel pump and an air blower, connections for entering air from said blower into said combustion chamber through one of its end walls and directing it toward its opposite end wall, an oil atomizing nozzle supplied by said fuel pump for entering a spray of oil into said combustion chamber adjacent that end wall of said chamber through which the air is entered, which nozzle is so positioned as to mix such spray with the air being so entered and is adapted to form an oil spray of such shape as will produce a flame of such pattern in said combustion chamber that it is in out of contacting relation to the walls of such chamber, and air admission means for supplying air from said blower to said outer chamber for flow therethrough to the discharge opening of said outer chamber in contact with the walls of said combustion chamber and in such amounts as to maintain a pressure in said outer chamber which is less than the pressure maintained in said combustion chamber by said blast of mixture entered into said combustion chamber and combustion of said mixture therein whereby to prevent flow of air through said perforations into said combustion chamber.

4. Apparatus according to claim 3 in which the end wall of the combustion chamber opposite the end wall thereof through which the air is entered into said chamber also is formed with a multitude of spaced small perforations, which perforations and those of the lateral walls of said chamber constitute substantially the sole means of discharge of combustion products from said chamber.
